UNITED STATES PATENT OFFICE.

WILLIAM HUDDLE, OF MANSFIELD, OHIO, ASSIGNOR TO THE AULTMAN & TAYLOR MACHINERY COMPANY, OF MANSFIELD, OHIO, A CORPORATION OF OHIO.

PULLEY.

1,170,755.

Specification of Letters Patent.

Patented Feb. 8, 1916.

Application filed June 24, 1915. Serial No. 36,063.

To all whom it may concern:

Be it known that I, WILLIAM HUDDLE, a citizen of the United States of America, residing at Mansfield, in the county of Richland and State of Ohio, have invented certain new and useful Improvements in Pulleys, of which the following is a specification.

This invention relates to a method or 10 means of building and constructing pulleys.

The primary object of this invention is to construct a pulley of wood and metal by providing a metal hub which is adapted to carry and retain a series of longitudinal 15 wooden bars to form the periphery of the pulley.

Further objects are to provide means of 20 securely clamping a series of longitudinal wooden bars to a metal hub, thereby forming segmental portions of the periphery of a pulley and leaving interstices between the bars, which in combination with the wooden 25 surfaces of the bars permits the air to escape and prevents it from forming air cushions between the belt and that portion of the periphery of the pulley with which it is in contact; provides maximum working adhesion and close contact of the belt with the 30 pulley; permits elastic contact of the belt with the periphery of the pulley and provides a gripping contact between the edges of the bars and belt; said attributes not being common in the conventional type of 35 metal or wood pulley, (especially the smaller sizes).

Another object is to provide a method of 40 building a pulley that will retain all the advantages of a wooden pulley and eliminate its disadvantages such as warping, expanding and contracting of the wood, which has the effect of throwing the periphery out of 45 true, thereby preventing the proper transmission of power or pressure of the belt upon the periphery of the pulley.

45 A further object is to provide means of varying the width of the face and diameter of the pulley easily, conveniently and rapidly by an interchange of the longitudinal wooden bars forming the periphery of the 50 pulley without removing the pulley from the shaft upon which it is mounted.

This invention further obviates the necessity of facing the periphery of the pulley with leather or the like to present a more 55 elastic and adhesive surface to the belt.

I attain these and other objects by the mechanism illustrated in the accompanying drawing in which—

Figure 1. is an end view showing the detail of the assembly of the pulley; Fig. 2. 60 is a vertical side elevation of Fig. 1 on the line X X showing a part of the periphery omitted and in section to show its construction more clearly.

In the drawing reference numeral 1 represents a hub provided with cupped shaped 65 annular undercut recesses 2 and 3 forming sleeve like projections 4 and 5. A series of longitudinal radial ridge flanges 6 extend from the periphery of the undercut projections and the hub forming tapered pockets 7 to receive a series of longitudinal peripheral wooden bars 8 and maintain them 70 spaced apart leaving interstices 9 between the edges of each unit thereof. The bars are 75 securely clamped in place by the slotted bolts 10 which pass through apertures in each end of the bars, and by the manipulation of the nuts 11 draw and retain the bars 80 snugly within the tapered pockets. To provide for truing up the periphery of the bars as occasion may require, the apertures in the bars are countersunk as shown. The dotted 85 lines 12 and 13 represent different heights of the longitudinal wooden bars which may be interchanged to vary the diameter of the pulley and the dotted lines 14 and 15 represent different lengths of the bars which may interchange to vary the width of the face of the pulley. The cupped shaped ends of the 90 hub produce an inclosure for the ends of the bolts and nuts and affords facilities for manipulating them as desired.

I claim:

1. The combination in a pulley, of a hub 95 having its ends cup-shaped and also having a series of radial plane surface longitudinal flanges extending from the periphery of the hub to form V shaped open pockets, and a series of plane surface longitudinal bars 100 spaced apart by said flanges and clamped in the pockets thereby forming the periphery of the pulley.

2. In a pulley, a metal hub having its 105 ends undercut, said hub also having a series of radial longitudinal flanges extending from the periphery of the hub to form a series of plane surface and tapered radial open pockets, a series of plane surface longitudinal wooden peripheral bars fitted to said 110

pockets in spaced relation with respect to each other, and fastening means provided on each end of the bars to retain said bars in said pockets.

3. In a pulley, a hub having its ends cup-shaped and also having a series of radial plane surface flanges provided on the hub forming open pockets, a series of plane surface longitudinal wooden bars fitted to said pockets and held in spaced relation from each other by said flanges, and means to secure said bars in said pockets.

4. In a pulley a cup-shaped metal hub provided with a series of radial plane surface and open pockets, and a series of plane surface longitudinal wooden bars which are inserted in said pockets in spaced relation from each other to form the periphery of the pulley with interstices between the 20 wooden bars.

5. The herein described pulley, comprising a cup-shaped metal hub provided with a series of plane surface radial pockets, a series of plane surface longitudinal wooden bars which are inserted in said pockets to

form the periphery of the pulley with interstices between the bars thereby forming a pulley of metal and wood, and a clamping means which affords facilities for interchanging said wooden bars by lifting them 30 from their respective pockets and replacing them with others to vary the diameter and the face of the pulley without removing the pulley from the shaft upon which it is mounted.

6. In a pulley, constructed of metal and wood, a series of plane surface wooden bars in combination with a hub having a series of plane surface open pockets provided upon its periphery which are adapted to receive 40 said series of wooden bars therein; said bars being held in spaced relation from each other by the walls of the pockets, and means to securely clamp said bars in said pockets as described and set forth.

In testimony whereof I affix my signature in presence of a witness.

WILLIAM HUDDLE.

Witness:

JOHN H. Coss.
